UNITED STATES PATENT OFFICE.

EDWARD J. BRENNAN, OF OELWEIN, IOWA, AND LAWRENCE L. NEEBE, OF WOODBURY, NEW JERSEY.

LOCOMOTIVE FRAME.

Application filed October 22, 1927. Serial No. 227,916.

The object of our invention is to make a locomotive frame, of the type in which the cylinder structure is located between upper and lower arms of the frame, in such manner that it can be made as an integral casting which can be machined, and then cut to allow for the insertion of the cylinder structure, the cut portion being replaced and welded or otherwise secured at the point where it had been previously cut.

In the accompanying drawing:

Fig. 1 is a side view of a locomotive frame made in accordance with our invention;

Fig. 2 is an enlarged side view of the front end of the frame;

Fig. 3 is a transverse sectional view of the two side frames on the line 3—3, Fig. 2, showing the cylinder structure in position; and

Fig. 4 is a detached side view of the upper arm which has been severed from the main casting to allow for the insertion of the cylinder structure.

1 is a frame having the usual pedestals 2 connected together by portions 3. The forward end of the frame is forked, 4 being the lower arm and 5 the upper arm. These arms are spaced apart to fit the cylinder structure 6 shown in Fig. 3.

The cylinder structure in the present instance is the ordinary two-cylinder structure of a high-pressure locomotive, but it will be understood that any type of cylinder structure may be used without departing from the essential features of the invention.

The arms of the frame are secured to the cylinder structure by bolts in the present instance, as shown in Fig. 3. Shoulders 7 and 8 on each arm 4 and 5, respectively, of the frame fit against the ends of the cylinder structure. The end portions of the arms 4 and 5 are located close together and extend parallel one with the other as illustrated at 4^a and 5^a, Fig. 2. The foot plate of the locomotive is located between the end portions of the arms, and the arms are perforated for the passage of securing bolts.

The frame casting 1 is made as a unitary structure and the entire frame machined while the parts are integral, thus insuring accuracy. After the frame has been completed, the upper arm 7 is severed on the line x—x, Fig. 2, and entirely removed as shown in Fig. 4. This allows a free opening for the introduction of the cylinder casting 6, which is located on the lower arm 4 of the frame

between the shoulders 7 and 8 of the said lower arm.

After the cylinder structure has been placed in position, then the upper arm 5 is located in position on the cylinder casting, 60 with the severed end abutting that of the main frame. Then the two parts which were previously severed are welded or otherwise secured on the line x—x, Fig. 2, so that the casting becomes an integral structure with 65 the cylinder structure located in proper position, the welding being preferably accomplished after the arm 5 has been securely fastened to the cylinder structure. While it is preferable to sever the upper arm 5 from the 70 frame 1, in some instances the lower arm may be severed from the frame and the cylinder structure inserted in position and secured to the upper frame, after which the arm is then welded or otherwise secured to 75 the frame at the point where it had been previously severed.

The particular design of frame will vary with the particular type of locomotive.

We claim:

1. The process herein described of assembling locomotive frames and cylinder structures, said process consisting in making a frame having two integral arms at one end; machining the entire frame including the 85 arms; then severing one of said arms from the frame; locating the cylinder structure in position; then replacing the severed arm; and securing the arm permanently to the frame at the point where it was severed. 90

2. The process herein described of assembling locomotive frames and cylinder structures, said process consisting in making a frame having two integral arms at one end; machining the entire frame including the 95 arms; then severing one of said arms from the frame; locating the cylinder structure in position and securing it to the other arm; then replacing the severed arm, securing it to the cylinder structure; and securing the arm 100 permanently to the frame at the point where it was severed.

3. The process herein described of assembling locomotive frames and cylinder structures, said process consisting in making the 105 side frames of the locomotive with pedestals and two arms at the forward end spaced apart for the reception of a cylinder structure; severing the upper arm from the frame; removing said arm; placing the cylinder 110

structure in position on the lower arm and securing it in position on said arm; then mounting the severed upper arm on the cylinder structure with the severed end of the frame; securing said arm to the cylinder structure; and welding the abutting ends of the frame and arm together to form a unitary structure.

4. A locomotive frame made in a single casting, said frame having pedestals and two longitudinal arms spaced apart at the forward end and shaped to fit a cylinder casting, one of the arms being so formed that it can be severed between the part to be secured to

a cylinder and the first pedestal, to allow for 15 the insertion of the cylinder, and then replaced in position and welded to the frame.

5. A locomotive frame made in a single casting, and having two arms at the forward end, one arm being directly above the other 20 arm, said arms being spaced apart for the reception of a cylinder structure, each arm having a shoulder at each end arranged to abut the cylinder structure, said arms having parallel extensions spaced apart for the re- 25 ception of a foot plate of the locomotive.
